(57) **CLAIM**

The ornamental design for an aircraft tail, as shown and described.

DESCRIPTION

FIG. 1 is a front, left perspective view showing an aircraft tail according to my new design;

FIG. 2 is a top plan view of the aircraft tail of FIG. 1;

FIG. 3 is a bottom plan view of the aircraft tail of FIG. 1;

FIG. 4 is a front elevation view of the aircraft tail of FIG. 1;

FIG. 5 is a rear elevation view of the aircraft tail of FIG. 1;

FIG. 6 is a left elevation view of the aircraft tail of FIG. 1;

FIG. 7 is a right elevation view of the aircraft tail of FIG. 1; and,

FIG. 8 is a front, left perspective view of the aircraft tail of FIG. 1 shown with propellers.

Throughout the Figures, broken lines showing environment or structure are for illustrative purposes only and form no part of the claimed design.

1 Claim, 8 Drawing Sheets
